UNITED STATES PATENT OFFICE.

WILLIAM A. WILLIAMS, OF BARTON, OHIO.

LOCK FOR THE GATES OF ELEVATOR-SHAFTS.

1,170,032.

Specification of Letters Patent.

Patented Feb. 1, 1916.

Application filed April 19, 1915. Serial No. 22,228.

To all whom it may concern:

Be it known that I, WILLIAM A. WILLIAMS, a citizen of the United States of America, and resident of Barton, county of Belmont, and State of Ohio, have invented certain new and useful Improvements in Locks for the Gates of Elevator-Shafts, of which the following is a specification.

This invention relates broadly to gates for elevator shafts, and specifically to a gate and automatically controlled locking means therefor.

The primary object of the invention is to provide a gate for elevator shafts having mechanism whereby it is normally maintained locked, and associated with means whereby, when the elevator occupies a predetermined level, said locking mechanism is automatically rendered inoperative, permitting the gate to be opened.

A further object is to provide locking means designed particularly for use on the gates employed at the mouths of mine shafts, whereby the opening of such gate is effectually prevented until the elevator or cage assumes a predetermined position in relation to said gate.

A further object is to provide, in connection with the gate-locking mechanism mentioned, means whereby the condition of said gate is indicated at a distant point—that is to say, an indicator located at a point, as in the engine room, has connection with the gate-locking mechanism and is designed to visually indicate whether the gate is in open or closed position, or, rather, in locked or unlocked condition.

With these and other objects in view, the invention resides in the features of construction, arrangement of parts and combinations of elements which will hereinafter be fully described, reference being had to the accompanying drawings, forming a part of this specification, in which—

Figure 1 is a front elevation of a gate equipped with my improved locking mechanism, the electric control and indicator circuits being illustrated diagrammatically; Fig. 2 is an enlarged front elevation of the locking mechanism with the casing removed; Fig. 3 is a section on the line 3—3, Fig. 2; and Fig. 4 is an enlarged detail view of the circuit closer.

Referring to said drawings, in which like designating characters distinguish like parts throughout the several views—1 indicates

generally an elevator or cage and 2 the cage guides, said parts being of an ordinary or any suitable type. Hinged upon a post 3 at the mouth of the shaft in which the cage operates is a gate 4 having one end of a latch-bar 5 pivotally mounted thereon, said bar being extended through a suitable keeper 6 in which it is vertically movable. Mounted on the outer face of the opposite gate post 7 is a base-plate 8 which adjacent to its upper end has an angular formation whereby is provided between an upright portion 8^a and said post 7 a substantially rectangular pocket 9 designed for the reception of said bar 5, the latter being adapted to be moved vertically into and out of said pocket to respectively latch and unlatch said gate. Fixed upon said base-plate 8 is an outwardly extending bracket or support 10 upon the outer end of which a substantially upright bar 11 is pivotally mounted, the pivotal point 12 being intermediate the ends of said bar. Fixed upon the upper end of said bar is the outer end of a horizontally disposed latch or locking-bar 14 the inner end of which projects into interlocking engagement with latch-bar 5 when the latter occupies a position in pocket 9, said locking bar 14 being operable through a suitable opening 13 provided therefor in the upright portion 8^a of the base-plate and having its said inner end received in an opening 15 provided therefor in said latch-bar 5. A suitable retractile coil spring 16 connected at one end to the pivoted bar 11 above its pivotal mounting and at its opposite end to a suitable fixed point, as a post 17 fixed to the supporting bracket 10, serves to normally maintain said bar in a position where the locking-bar 14 occupies locking position.

Mounted upon the base-plate 8 adjacent to its lower end is an electromagnet 18 which, when energized, attracts an armature 19 carried by the lower end of the pivoted bar 11, causing the latter to swing on its pivot 12 and to withdraw the locking bar 14 from interlocking relation with the pivoted latch-bar 5, whereupon the latter may be elevated to open the gate. Said electromagnet 18 is included in a normally open electric circuit one side of which leads to said magnet from a suitable source of electrical energy, as a battery 20, through a conductor 21. The opposite pole of said battery is connected by a conductor 22 to a contact piece 23 forming

a part of a circuit closer which is generally designated by the numeral 24. Said circuit closer comprises a small plate or panel 25 of a non-conductive material, as fiber, 5 mounted in a stationary position on one side of one of the cage-guides 2 at a suitable point. Fixed upon said plate 25 at separated points is said contact 23 and a similar contact 26, the latter being connected to the 10 magnet 18 by a conductor 27. Extending through said plate 25 are the ends of one or more horizontally disposed pins 28 the opposite ends of which carry thereon a metallic bridge-piece 29. Carried by each of said pins 15 is an encircling spiral spring 30, said springs being designed to normally maintain said bridge-piece thrust outward to a position out of engagement with said contacts 23 and 26. Said bridge, which has its ends beveled 20 for the purpose, is designed to be engaged by the curved face of a bumper 31 which is mounted at a suitable point on the cage 1, when said cage closely approaches its loading and unloading position at the mouth 25 of the shaft. When so engaged, said bridge is forced outward against the tension of the springs 30 into engagement with contacts 23 and 26, bridging the intervening open space and closing the electric circuit. Thus, during 30 the time that the cage occupies its proper position at the mouth of the shaft, said electric circuit remains closed, permitting the latch-bar 5 to be elevated for opening the gate. When, however, the cage has moved 35 slightly from said proper position, the bumper is withdrawn from engagement with the bridge and the circuit is opened, preventing opening of the gate. A suitable switch, as 32, may be provided in the circuit 40 whereby the circuit may be broken for rendering inoperative the automatic latch-bar releasing mechanism described.

A suitable casing 33 is fitted over the locking mechanism, as shown in Fig. 3. 45 A key-hole 34 is provided at a suitable point in said casing, the same being designed to permit of the introduction of a key whereby the lower end of the pivoted bar 11 may be swung inward for unlocking 50 the gate. Such key will of course be carried by an attendant or one in authority in order that the gate may be opened at the lower mine levels.

For visually indicating to the engineer, 55 or other person whose duty it is to raise or lower the cage, whether the gate occupies open or closed position, a second electric circuit is provided, said circuit including an indicator, as the dial indicator 35 of a common type, located at an appropriate point, as in the engine room. Said circuit comprises a battery 36 or other source of electrical energy, a conductor 37 leading from said battery, an upright copper contact post 60 65 38 stationarily disposed in a fiber sheath 39

mounted on the base-plate 8 at a suitable point, a copper post 40 mounted in a fiber sheath 41 carried on one end of a lever 42 which is mounted intermediate its ends upon a pivot pin 43 supported by a bracket 44 70 mounted on said base-plate. The opposite end of said lever 42 normally projects upward into the pocket 9, a retractile coil spring 45 being arranged to normally hold said lever in a position wherein contact 75 post 40 engages contact post 38. Said conductor 37 connects to said contact 38, and a conductor 46 leads from said contact 40 to the indicator 35 which is connected by a conductor 47 to the battery 36. When the 80 latch-bar 5 is dissociated from the locking mechanism, the lever 42 occupies the position shown in Fig. 2, wherein the inner end thereof is projected upward into pocket 9 and the opposite end is lowered holding 85 contact 40 in engagement with contact 38, closing the indicator circuit which actuates the pointer of dial 35 to stand at the "open" position. When the gate is closed and the latch-bar is dropped into pocket 9, the 90 weight of the outer end of the latter depresses the inner end of the lever 42 and raises the opposite end of said lever against the tension of its spring 45, elevating contact 40 out of engagement with contact 38 95 and breaking the electric circuit to the indicator 35, the pointer of which normally stands at "shut" position indicating that the gate is closed.

It will be noted that various changes or 100 alterations may be made in the form and arrangement of some of the parts composing my apparatus without departing from the general spirit or scope of the invention 105 as defined in the appended claims. 105

What is claimed is—

1. The combination with an elevator and a gate guarding the entrance to an elevator shaft, of a latch-bar carried by said gate, a stationary member having a pocket for receiving said latch-bar when the gate is closed, means for indicating the position of said latch-bar, the last-mentioned means comprising a normally closed electric circuit, a signal and a pair of contacts located in said circuit, a pivoted lever supporting one of said contacts, and means normally maintaining said lever in a position wherein said contacts engage, said lever having a part directed into said pocket and adapted to be depressed by the seated latch-bar for swinging said lever to a point separating said contacts. 120

2. The combination with an elevator and a gate guarding the entrance to an elevator shaft, of a latch-bar carried by said gate, a stationary member having a pocket for receiving said latch-bar when the gate is closed, means for locking said latch-bar in said pocket, a normally closed electric cir- 125 130

cuit, a dial indicator in said circuit, a pair of contacts in said circuit, a pivoted lever supporting one of said contacts, means normally maintaining said pivoted lever in a position wherein said contacts lie in engagement, said lever having a projection extended into said pocket and adapted to be depressed by introduction of said latch-

bar into said pocket for swinging said lever to a point separating said contacts.

In testimony whereof, I affix my signature in presence of two subscribing witnesses.

WILLIAM A. WILLIAMS.
